No. 893,430.

PATENTED JULY 14, 1908.

M. F. BONZANO.

COMPOSITE RAILROAD CROSS TIE.

APPLICATION FILED MAY 7, 1907.

UNITED STATES PATENT OFFICE

MAXIMILIAN F. BONZANO, OF GOSHEN, VIRGINIA, ASSIGNOR TO PENN RAILROAD TIE COMPANY, OF CAMDEN, NEW JERSEY, A CORPORATION OF NEW JERSEY.

COMPOSITE RAILROAD CROSS-TIE.

No. 893,430.

Specification of Letters Patent.

Patented July 14, 1908.

Application filed May 7, 1907. Serial No. 372,331.

To all whom it may concern:

Be it known that I, MAXIMILIAN F. BONZANO, a citizen of the United States, and a resident of Goshen, Rockbridge county, Virginia, have invented certain Improvements in Composite Railroad Cross-Ties, of which the following is a specification.

The object of my invention is to provide a railroad cross-tie of composite character designed to take advantage of the strength and other valuable properties of metal, and the resiliency of wood or other fibrous material; these several elements being combined in a novel manner and producing a most satisfactory structure for the purpose described.

My invention is fully shown in the accompanying drawings, in which:

Figure 1, is a view in elevation of a composite tie made in accordance with my invention; Fig. 2, is a plan view of the same; Fig. 3, is a sectional view, taken on the line *a—a*, Fig. 1; Fig. 4, is a sectional view, taken on the line *b—b*, Fig. 2; Fig. 5, is a view illustrating a detail of my invention, and Fig. 6, is a perspective view illustrating a further detail of my invention.

In my patent, No. 844,774, dated February 19, 1907, I have described and claimed a metallic cross-tie comprising a channel beam or trough section, the web of which is laid horizontally and centrally cut, and the metal on opposite sides of said cut displaced toward the side walls of such channel beam. The ends of the channel beam are crimped or otherwise closed so that between said ends and the centrally displaced upper web, ballast holding pockets are provided.

In the tie forming the subject of my present invention, I propose to use channel beams or trough sections of substantially the same type shown and described in my patent above referred to, having the central portion of the upper web slit and all or part of the metal on opposite sides of the same displaced towards the side walls.

In the present instance, in addition to the centrally disposed slit, the web 1 of the channel beam or trough section forming the tie, is cut out at the points 2, adjacent the ends of the same, to receive blocks of wood or other fibrous material 3 upon which the rails rest, and to which the rails may be fastened in any approved manner. To support these blocks, the under space in the channel beam tie at the ends of the same and directly be-

low these blocks 3 contains filling means, such means in one instance comprising a pair of blocks 4, and a wedging block 5, as shown in Fig. 3; and in the other instance, a single block 6, as shown in Fig. 5. The blocks 4 lie against and approximately parallel with the walls of the channel beam or trough section, while the block 5 fits the space formed between the blocks 4 and keys the latter in place. The blocks are further held in place by the rail fastenings, and if a series of blocks are used, they will be wedged into the cavity of the cross-tie by the vertical pressure and reaction of the ballast or road-bed, for example. As the blocks within the channel beam tie rest upon the road-bed or ballast they are thereby supported, and such support being communicated to the upper block 3 upon which the rails rest, the latter are provided with a resilient foundation and do not depend at all for their vertical support upon the metallic portion of the tie.

The side walls of the channel beam or trough section forming the tie are flanged at 8 and are confined against spreading by one or more clamps 9, as clearly shown in Figs. 1, 2 and 3, and the block or blocks mounted in the ends of such channel beam or trough section and confined against sidewise displacement by these clamps, which also aid in preserving the shape of the trough section or shell, may be driven in and out when necessary. The blocks are so made as to rest upon these clamps as far as necessary to hold them in place, and may have undercut portions 10 between the portions engaging the clamps into which the ballast of the road-bed will be tamped or find its way and serve as additional means for retaining the tie in place.

To prevent endwise displacement of the blocks 4 and 5 with respect to the channel beam or trough section, I provide bolts 11, passing through the tie and through the block or blocks, in the manner shown in the drawing. Or I may close the end of the tie 100 by a plate 12, suitably secured in place, as shown in Fig. 6, as may be most convenient or desirable, and allow the blocks 4 and 5, or 6, to abut against said closure.

The rails are preferably fastened to the blocks 3 and the blocks supporting the same by means of headed lag screws or bolts 13 passing through such rail supporting blocks and into or through the blocks 5 or 6 below the same. In some instances, I may secure 110

the rail supporting blocks 3 to the block or blocks below the same by means of spikes 14, as indicated in the drawing. Other forms of fastenings may be employed, however, without departing from my invention.

In Fig. 5, I have shown a structure in which a single block 6, confined by the channel beam or trough section, is employed beneath the rail supporting blocks 3 instead of the series 10 shown in Fig. 3. In this instance, the block 6, carries the fastenings for securing the rails to the blocks 3, such fastenings being in the form of bolts 15, with or without rail engaging or fastening heads, which pass through the rail 15 supporting block and block 6; and being confined thereto by nuts 16 which are countersunk in such block. The blocks 6 will also be retained against endwise displacement in the tie by the bolts 11 at the ends of 20 the same, or by the closure 12 shown in Fig. 6. If desired, the blocks 6 may be made in two horizontal layers, and the nuts 16 countersunk into either one of the contacting faces. These nuts may be tapped to receive 25 one of the bolts, or an elongated nut may be employed tapped to receive two bolts 13 mounted adjacent each other on one side of the rail.

The blocks 3, of wood or other fibrous material, are preferably provided with metallic wear plates 17 for contact with the rail bases.

I claim:

1. In a composite tie, the combination of a metal channel beam or trough section, resilient rail-supporting blocks disposed in apertures in the top web of said beam and projecting above the same, and blocks confined by said beam and in contact with the road-bed upon which said rail-supporting blocks are 40 mounted.

2. In a composite tie, the combination with a metal channel beam or trough section having its top web partly slit and the metal on opposite sides of said slit displaced towards the side walls of the same, said web being apertured adjacent its ends, of rail-supporting blocks disposed in said apertures, and blocks in contact with the road-bed and confined by said beam upon which said rail-supporting blocks are mounted, such construction providing ballast holding pockets between the blocks in contact with the road-bed and the displaced portion of the top web.

3. In a composite tie, the combination with a metal channel beam or trough section having the central portion of its top web slit and the metal on opposite sides of said slit displaced towards the side walls of the same, said web being apertured adjacent its ends, 50 of resilient rail-supporting blocks disposed in said apertures, and resilient blocks in contact with the road-bed and confined by said beam upon which said rail-supporting blocks are mounted, such construction providing ballast holding pockets between the blocks in

contact with the road-bed and the displaced portion of the top web.

4. In a composite tie, the combination with a metal channel beam or trough section having its top web partially slit and the metal on opposite sides of said slit displaced towards the side walls of the same, said web being apertured adjacent its ends, of resilient rail-supporting blocks disposed in said apertures, resilient blocks in contact with the road-bed and upon which said rail-supporting blocks are mounted, and means for confining said blocks together and to the tie.

5. In a composite tie, the combination with a metal channel beam apertured adjacent its ends, of resilient rail-supporting blocks disposed in said apertures and projecting above the tie, supplemental blocks contacting with the road-bed upon which the rail-supporting blocks are mounted, said supplemental blocks being disposed between the walls of the tie, and means for securing the rail-supporting blocks to said supplemental blocks.

6. In a composite tie, the combination with a metal channel beam apertured adjacent its ends, of resilient rail-supporting blocks disposed in said apertures and projecting above the tie, supplemental blocks contacting with the road-bed upon which the rail-supporting blocks are mounted, said supplemental blocks being disposed between the walls of the tie, means for securing the rail-supporting blocks to the supplemental blocks, and clamping members engaging the tie and serving to maintain the supplemental blocks in proper position with relation thereto.

7. In a composite tie, the combination with a metal channel beam apertured adjacent its ends, of resilient rail-supporting blocks disposed in said apertures and projecting above the tie, supplemental blocks contacting with the road-bed upon which the rail-supporting blocks are mounted, said supplemental blocks being disposed between the walls of the tie, means for securing the rail-supporting blocks to the supplemental blocks, clamping members engaging the beam and serving to vertically support the supplemental blocks and maintain them in proper position with relation to the tie, and means in engagement with the tie for holding the supplemental blocks under the rails and at a fixed distance with respect to each other.

8. In a composite railroad tie, the combination of a metallic member of inverted channel conformation, sets of resilient blocks for supporting the rails disposed within said member and projecting through apertures in the same, securing means for engaging said rails adapted to enter said resilient blocks, and bolts passing transversely through said blocks to prevent displacement of the same with respect to said channel member, said blocks contacting with and

receiving their support directly from the road-bed.

9. In a composite railroad tie, the combination of resilient rail supporting means, rail securing devices adapted to be passed into said resilient means, a metallic member disposed over said resilient means and retained therewith and extending downwardly into the road-bed, said resilient means including rail-supporting blocks lying within the metallic member and in contact with the road-bed and projecting through and extending above the metallic member.

10. As a new article of manufacture, a railway-tie consisting of an inverted U-shaped channel-iron having flanges at the outer lower edges of its side walls for engagement with the road-bed, resilient rail supporting blocks adapted for the reception of rail fastenings disposed within the ends of the tie and in contact with and supported directly by the road-bed, and clamp-plates underlying the tie and blocks and in engagement with said flanges.

11. A composite railway-tie, consisting of an inverted hollow channel-iron having apertures in its web, flanges formed upon the lower edges of the side walls of said channel-iron, resilient blocks for the reception of rail fastenings fitted in the ends of the channel-

iron and projecting through the apertures of the same, and clamp-plates adapted to engage said flanges to hold said resilient blocks in place and prevent the spreading of the tie, said blocks being in contact with and supported directly by the road-bed.

12. A composite tie, comprising an inverted channel beam or trough section having apertures, and resilient rail supporting means in contact with and supported directly by the road-bed projecting through said apertures above the top web of said channel beam, said rail supporting means being confined by said channel beam.

13. A composite tie, comprising a channel beam or trough section having apertures, fibrous rail supporting blocks disposed in said apertures and extending above the top web of said channel beam, and supplemental blocks confined by the channel beam for carrying the rail supporting blocks, said supplemental blocks being in contact with and supported directly by the road-bed.

In testimony whereof, I have signed my name to this specification, in the presence of two subscribing witnesses:

MAXIMILIAN F. BONZANO.
